(57) **CLAIM**

The ornamental design for the jigsaw puzzle peg, as shown and described.

DESCRIPTION

FIG. 1 is an exploded top perspective view of the jigsaw puzzle peg showing my new design;

FIG. 2 is an exploded bottom perspective view thereof;

FIG. 3 is an exploded side elevational view thereof;

FIG. 4 is an exploded side elevational view rotated 90° from FIG. 3;

FIG. 5 is a bottom plan view of each of the separated parts shown in FIGS. 1-4;

FIG. 6 is a top plan view of FIG. 5;

FIG. 7 is a side elevational view showing the design assembled and attached to a jigsaw puzzle piece;

FIG. 8 is a top plan view of FIG. 7; and,

FIG. 9 is a bottom plan view thereof.

The broken line showing of the puzzle piece is included for the purpose of illustrating environmental structure and forms no part of the claimed design.
